DESIGN FOR A CARD TIME RECORDER

George H. Kress, Vestal, N. Y., assignor to International Business Machines Corporation, New York, N. Y., a corporation of New York

Application March 1, 1948, Serial No. 144,854

Term of patent 14 years

(Cl. D64—11)

To all whom it may concern:

Be it known that I, George H. Kress, a citizen of the United States, residing at Vestal, in the county of Broome and State of New York, have invented a new, original, and ornamental Design for a Card Time Recorder, of which the following is a specification, reference being had to the accompanying drawing, forming part thereof.

Figs. 1, 2 and 3 are, respectively, a front elevation, a plan view, and a perspective view of a card time recorder, showing my new design.

I claim:

The ornamental design for a card time recorder, as shown.

GEORGE H. KRESS.
